UNITED STATES PATENT OFFICE.

THOMAS L. LOFLAND, OF KANSAS CITY, KANSAS.

WINDOW-SHADE BRACKET.

1,090,319.

Specification of Letters Patent. Patented Mar. 17, 1914.

Application filed November 9, 1909, Serial No. 526,985. Renewed November 10, 1913. Serial No. 800,227.

To all whom it may concern:

Be it known that I, THOMAS L. LOFLAND, a citizen of the United States, residing at Kansas City, in the county of Wyandotte 5 and State of Kansas, have invented certain new and useful Improvements in Window-Shade Brackets, of which the following is a specification.

This invention relates to window shade 10 brackets, and one of the principal objects of the invention is to provide simple, reliable, efficient and inexpensive means for supporting a window shade which will not mar the window casing in attaching the 15 same thereto.

Another object of the invention is to provide a window shade bracket, each member of which is made from a single piece of wire having a threaded or gimlet pointed 20 shank and one of said members having a squared bearing for the rectangular pintle of a shade roller, while the other member is provided with a rounded bearing comprising a series of coils slightly separated 25 one from the other in order to provide a spring thrust bearing for the rounded pintle of the shade roller.

Still another object of the invention is to provide a pair of bracket members which 30 can be readily connected to a window frame in any desired position and which can be secured in place without the means of a screw driver, hammer or other tool.

These and other objects may be attained 35 by means of the construction illustrated in the accompanying drawing, in which—

Figure 1 is a front elevation of a window having a shade mounted thereon, said shade being supported by brackets made in accordance 40 with my invention. Fig. 2 is a perspective view of one of the bracket members. Fig. 3 is a similar view of the other bracket member.

Referring to the drawing the numeral 1 45 designates a window casing; 2 is a shade roller which may be of the usual or any suitable construction, said roller having a squared pintle 3 projecting from one end thereof and a round pintle 4 extending from 50 the opposite end thereof, in the usual manner. The window shade 5 is connected to the roller 2 in the usual or any suitable manner.

As shown in Fig. 2 the bracket member 55 A for the squared pintle 3 is provided with a plain shank 6 having a threaded or gimlet

pointed end 7. This member is preferably made from a single length of wire of the required gage, and is provided with a downwardly projecting arm 8 which extends at 60 right angles to the shank 6 and is provided with a bearing member 9. Extending toward the shank 6 from the bearing member 9 is an arm 10 having an inwardly bent end 11.

The bracket member B, designed for the purpose of supporting the round pintle 4 of an ordinary window shade roller, is also made of a single length of wire of the required gage and provided with a shank 70 65 12 having a screw threaded or gimlet pointed end 13. The shank 12 is provided with two or more coils 14 at its outer end forming a bearing for the pintle 4. The coils 14 are separated a slight distance in 75 order that there will be a slight spring action when the end of the roller is thrust against the inner coil, to thus prevent binding of the roller in the bearing. The shanks 6 and 12 may each be provided with a 80 mark *a* to indicate the distance in which the shank may be inserted in the window casing so that both brackets will project a required distance to support the roller in proper alignment.

From the foregoing it will be obvious that the bracket member A can be readily connected either in a vertical position depending from the upper portion of the window casing or in a horizontal position connected 90 either to the window casing or to the sash, and that this member can be readily screwed in place by rotating the depending bearing for the squared pintle 3. The member B can also be connected to the casing or sash without the use of special tools.

If necessary the shank 6 of the member A can be inserted in the bearing formed by the coils 14 to turn the threaded portion 13 into the wood. In order to connect the 100 shade roller to the brackets the rounded pintle 4 is first inserted in the bearing formed by the coils 14. The squared pintle is inserted from underneath the shank through the passage way 15 into the squared 105 space 16 between the members 8 and 10 and cannot readily get out of place until it is lifted upward and pushed backward beyond the end 11, when it may be readily withdrawn from the member B.

My invention is of simple construction, 110 can be readily made of wire of proper gage,

can be quickly attached in any position required without the use of tools and does not mar or injure the window casing or sash in attaching.

5 Having thus fully described the invention what is claimed as new is:

A window shade bracket member made from a single length of wire having a gimlet-pointed shank, said shank terminating at 10 its outer end in a series of spiral coils, said coils being disposed toward the roller and below the horizontal plane of the shank, said coils separated one from the other to form a spring thrust bearing for the roller, 15 the terminal coil bearing against the end

of the shade roller to form a frictional brake for the latter, said coils serving as a finger hold for screwing the bracket into the window casing, and said shank provided with a mark to indicate the distance 20 in which said shank may be inserted in the casing in order that the brackets will support the roller in proper alinement.

In testimony whereof I affix my signature in presence of two witnesses.

THOMAS L. LOFLAND.
